(57) CLAIM

The ornamental design for a liquid and lotion container, as shown and described.

DESCRIPTION

FIG. 1 is a perspective view of a liquid and lotion container illustrating my new design;

FIG. 2 is a top view thereof;

FIG. 3 is a front elevational view thereof;

FIG. 4 is a bottom view thereof; and,

FIG. 5 is a left side view thereof.

The right side view is identical to the left side view.
